Patented Sept. 13, 1955

175,547

DOUGHNUT COOKER OR SIMILAR ARTICLE

Ruth G. Josephson, Middletown, R. I.

Application May 27, 1954, Serial No. 30,698

Term of patent 14 years

(Cl. D81—10)

Fig. 2

Fig. 1 is a front perspective view of a doughnut cooker or similar article showing my new design.

Fig. 2 is a front perspective view of the doughnut cooker as shown in Fig. 1 in open position.

The rear portion of the doughnut cooker is substantially plain; the other side is like the side shown.

The characteristic features of my design for the doughnut cooker disclosed reside in the handles on the sides and the upper front and in the control member on the lower front having the configuration shown.

I claim:

The ornamental design for a doughnut cooker or similar article, substantially as shown and described.
